TOY GUN AND CARTRIDGE HOLDER

Talley W. Nichols, Jacksonville, Tex.

Application April 10, 1957, Serial No. 45,662

Term of patent 14 years

(Cl. D34—15)

Fig. 1 is a front elevational view of a toy gun and cartridge holder, showing my new design;

Fig. 2 is a top plan view;

Fig. 3 is a cross-sectional view thereof taken on line 3—3 in Fig. 2; and

Fig. 4 is a perspective view thereof.

The broken line showing of a toy gun and cartridges in Fig. 1 is for illustrative purposes only.

I claim:

The ornamental design for a toy gun and cartridge holder, as shown and described.
